Brice G. Hadley, 262 Newton St., Denver, Colo.

Filed Apr. 6, 1962, Ser. No. 69,608

Term of patent 3½ years

(Cl. D42—7)

FIG. 1.

FIG. 3.

FIG. 4.

FIGURE 1 is a top plan view of a combined trophy and clock showing my new design;

FIGURE 2 is a front elevational view thereof;

FIGURE 3 is an end elevational view thereof; and

FIGURE 4 is a cross-sectional view thereof, taken on the vertical plane of line 4—4 of FIGURE 2, looking in the direction of the arrows.

The essential features of my design reside in the portion shown in full lines.

I claim:

The ornamental design for a combined trophy and clock, as shown and described.
